FIG. 4B

FIG. 4A

FIG. 5

1

CENTER MASS BELL APPARATUS AND
METHODS OF USING SAMEFIELD AND BACKGROUND OF THE
INVENTION

The present invention, in some embodiments thereof, relates to the exercise and fitness industry and, more particularly, but not exclusively, to a manual weightlifting apparatus and methods of using same.

U.S. Pat. No. 4,575,074 to Damratoski, the disclosure of which is incorporated herein, describes an exercise weight that has a handgrip and a hollow body disposed about the handgrip so that the mass of the body and of any material with which it might be filled will be evenly disposed about the hand of the user. The hand grip has a rectangular cross-section so as to engage the articulations of the hand. A flat surface is provided above the handgrip so that the weight can be rested upon the thumb and first finger of the user's hand. The outer walls of the body are sloped and join the bottom at an obtuse angle. The distance between the handgrip and one of the inner walls of the body is such that the device may be used as either a hand weight or a foot weight.

U.S. Pat. No. 7,014,598 to Fenelon, et al., the disclosure of which is incorporated herein, describes a dumbbell system including a base weight member having a ring-shaped body and a handle extending across an opening in the ring-shaped body. A plurality of weight rings are adapted to be removably mounted to the base weight member in order to provide a compact dumbbell system which has the capability of providing several weight increments in a compact assembly. The dumbbell system is ideal for use in areas where space is limited. The dumbbell also provides for a unique balanced mass arrangement which alleviates undesired stresses on a user's wrist.

U.S. Pat. No. 7,878,952 to Fenelon, the disclosure of which is incorporated herein, describes architectural parameters for the dimensions of sets of balanced circular free weights so that the weights may maintain a consistent style in appearance over a range of weights while retaining their functionality.

U.S. Pat. No. D438,265 to Fenelon, the disclosure of which is incorporated herein, describes the ornamental design for a dumbbell.

U.S. Pat. No. D480,438 to Walkow, the disclosure of which is incorporated herein, describes the ornamental design for an exercise weight.

SUMMARY OF THE INVENTION

There is provided in accordance with an exemplary embodiment of the invention, a center mass bell apparatus, comprising: a main body shaped substantially like a hollow sphere with spherical caps removed in a same central axis of the body to create two opposing openings and where the main body is balanced in at least three dimensions from a center point of the sphere; and, a hand hold traversing centrally through the hollow of the spherical main body transverse to the central axis.

In an embodiment of the invention, the apparatus has a height of 5.786 inches, an external diameter of 7.5 inches and a weight of 20 lb.

In an embodiment of the invention, the apparatus has a height of 7.006 inches, an external diameter of 8.5 inches and a weight of 35 lb.

2

In an embodiment of the invention, the apparatus has a height of 8.198 inches, an external diameter of 9.5 inches and a weight of 50 lb.

In an embodiment of the invention, the apparatus has a height of 9.365 inches, an external diameter of 10.5 inches and a weight of 70 lb.

In an embodiment of the invention, the hand hold is 1.0 to 2.5 inches in maximum diameter.

In an embodiment of the invention, the hand hold is 1.2 to 1.5 inches in maximum diameter.

In an embodiment of the invention, the ratio of the outer diameter squared to the height of the weight is under 21.

In an embodiment of the invention, the ratio of the weight to the square of the outer diameter times the height is under 0.08.

In an embodiment of the invention, the openings have a diameter of 4.5 inches.

In an embodiment of the invention, the hand hold has a circular cross-section.

In an embodiment of the invention, the hand hold has an oblong cross-section.

In an embodiment of the invention, the hand hold has an ovoid cross-section.

In an embodiment of the invention, the openings have at least one beveled edge.

In an embodiment of the invention, the main body and hand hold are of unitary construction.

In an embodiment of the invention, the apparatus manufactured by casting or injection moulding.

In an embodiment of the invention, the apparatus weighs between 5 lb and 200 lb.

There is further provided in accordance with an exemplary embodiment of the invention, a method of using a center mass bell apparatus, comprising:

inserting a hand through an opening to a hollow of the apparatus;

grabbing a hand hold located in the center of the hollow; and,

exercising by maneuvering the apparatus using the hand hold as the contact point between a user and the apparatus.

In an embodiment of the invention, the method further comprises stacking a plurality of apparatuses and exercising using the plurality of apparatuses simultaneously.

In an embodiment of the invention, the method further comprises repeating exercising.

Unless otherwise defined, all technical and/or scientific terms used herein have the same meaning as commonly understood by one of ordinary skill in the art to which the invention pertains. Although methods and materials similar or equivalent to those described herein can be used in the practice or testing of embodiments of the invention, exemplary methods and/or materials are described below. In case of conflict, the patent specification, including definitions, will control. In addition, the materials, methods, and examples are illustrative only and are not intended to be necessarily limiting.

BRIEF DESCRIPTION OF THE DRAWINGS

Some embodiments of the invention are herein described, by way of example only, with reference to the accompanying drawings. With specific reference now to the drawings in detail, it is stressed that the particulars shown are by way of example, are not necessarily to scale, and are for purposes of illustrative discussion of embodiments of the invention. In

this regard, the description taken with the drawings makes apparent to those skilled in the art how embodiments of the invention may be practiced.

In the drawings:

FIG. 1A is a side view of a 20 lb center mass bell apparatus, in accordance with an exemplary embodiment of the invention;

FIG. 1B is a top or bottom view of a 20 lb center mass bell apparatus, in accordance with an exemplary embodiment of the invention;

FIG. 2A is a perspective view of a 35 lb center mass bell apparatus, in accordance with an exemplary embodiment of the invention;

FIG. 2B is a side view of a 35 lb center mass bell apparatus, in accordance with an exemplary embodiment of the invention;

FIG. 2C is a top or bottom view of a 35 lb center mass bell apparatus, in accordance with an exemplary embodiment of the invention;

FIG. 3A is a side view of a 50 lb center mass bell apparatus, in accordance with an exemplary embodiment of the invention;

FIG. 3B is a top or bottom view of a 50 lb center mass bell apparatus, in accordance with an exemplary embodiment of the invention;

FIG. 3C is a side view of a 50 lb center mass bell apparatus showing a cross-section A-A of FIG. 3D, in accordance with an exemplary embodiment of the invention;

FIG. 3D is the cross-sectional view A-A of a 50 lb center mass bell apparatus, in accordance with an exemplary embodiment of the invention; FIG. 4A is a perspective view of a 70 lb center mass bell apparatus, in accordance with an exemplary embodiment of the invention;

FIG. 4B is a side view of a 70 lb center mass bell apparatus, in accordance with an exemplary embodiment of the invention;

FIG. 4C is a top or bottom view of a 70 lb center mass bell apparatus, in accordance with an exemplary embodiment of the invention; and,

FIG. 5 is a flowchart showing a method of using a center mass bell apparatus, in accordance with an exemplary embodiment of the invention.

DESCRIPTION OF SPECIFIC EMBODIMENTS OF THE INVENTION

The present invention, in some embodiments thereof, relates to the exercise and fitness industry and, more particularly, but not exclusively, to a manual weightlifting apparatus and methods of using same.

Before explaining at least one embodiment of the invention in detail, it is to be understood that the invention is not necessarily limited in its application to the details of construction and the arrangement of the components and/or methods set forth in the following description and/or illustrated in the drawings. The invention is capable of other embodiments or of being practiced or carried out in various ways.

Generally, a manually operated weightlifting apparatus is provided which is useable by any level of user, from a professional athlete to a fitness neophyte. In some embodiments of the invention, user safety, comfort and/or exercise efficiency are enhanced over what is currently available in the art by the weightlifting apparatuses described herein. In an embodiment of the invention, a centrally located hand hold (handle), accessible from at least two sides of the apparatus, creates a comfortable distribution of weight

around the hand and/or ensures there is no weight transfer and/or shifting as is common with traditional hand held weightlifting apparatuses. In an embodiment of the invention, this center mass bell configuration eliminates or at least reduces impact on wrists, hands, shoulders and/or other easily de-stabilized joints or muscle groups. While specific embodiments are described herein, it should be understood that some features and/or characteristics described with respect to one embodiment are capable of being applied to other embodiments.

In an embodiment of the invention, the spherical and/or compact design also provides for movements common to dumbbells without fear of rotating handles and/or dumbbell heads causing instability and/or limiting proper and/or safe range of motion. With a safer more effective range of motion using the center mass bell apparatuses described herein, the lifter is able to maximize not only their time under stress, but also experience more effective work under tension.

FIG. 1A is a side view of a 20 lb center mass bell apparatus 100, in accordance with an exemplary embodiment of the invention. A main body of the center mass bell apparatus 100 is shaped substantially like a hollow sphere with spherical caps removed in the same central axis 104, in an embodiment of the invention. In an embodiment of the invention, the size/diameter of the two spherical caps are the same. Optionally, the size/diameter of the two removed spherical caps are not the same. In an embodiment of the invention, the center mass bell apparatus 100 is manually operated by a user, that is the user grabs the apparatus 100 by a hand hold 102 through at least one opening 108 (opening 108 located on either and opposite sides) and maneuvers it without machine or automated assistance to derive exercise benefit. In an embodiment of the invention, maneuvering is at least one of lifting and lowering the apparatus. The center mass bell apparatus 100 is configured with the hand hold 102 traversing centrally through the hollow of the spherical main body, shown and described in more detail with respect to FIG. 1B and FIG. 3D. Optionally, the hand hold 102 traverses the hollow substantially transverse to the central axis 104 of the apparatus. In an embodiment of the invention, the hand hold 102 is circular in cross-section. In an embodiment of the invention, the hand hold 102 is oblong or ovoid or any other shape in cross-section. In some embodiments of the invention, the upper and/or inner edges of opening 108 are beveled to enhance user comfort and/or to provide stability and/or to allow for stacking of a plurality of center mass bell apparatuses 100.

In an embodiment of the invention, the main body and the hand hold are of unitary construction. For example, the main body and hand hold are formed through injection moulding or casting. In an embodiment of the invention, the main body and the hand hold are constructed of a metallic substance, for example iron, steel and/or an iron alloy. Optionally, the apparatus 100 is coated, for example with a polymer and/or rubber.

FIG. 1B is a top or bottom view of 20 lb center mass bell apparatus 100, in accordance with an exemplary embodiment of the invention. In an embodiment of the invention, the apparatus is equally balanced in weight in three axes from the center of the apparatus. That is, from the center of the apparatus, the weight distribution is the same in the x, y, and z axes.

In an embodiment of the invention, the center mass bell apparatus 100 has an approximate height of 5.786 inches and a radius from a center point of an imaginary sphere traced by the apparatus 100 of 3.75 inches (both shown in FIG. 1A), an external diameter of approximately 7.5 inches, and an

opening **108** diameter of approximately 4.5 inches (both shown in FIG. 1B). In an embodiment of the invention, the hand hold **102** is approximately 1.0-2.5 inches in maximum diameter. Optionally, the hand hold **102** is 1.2 inches in diameter.

It should be understood, that these dimensions are by way of example only, and that in different embodiments the dimensions are larger or smaller as long as three dimensional weight balance is maintained and that the ratio of the outer diameter squared to the height of the weight is under 21 and the ratio of the weight to the square of the outer diameter times the height is under 0.08. Optionally, the ratio of the outer diameter squared to the height of the weight is approximately 9.72. Optionally, the ratio of the weight to the square of the outer diameter times the height is approximately 0.06. In an embodiment of the invention, the opening **108** size is chosen to accommodate not just the insertion of a hand therethrough but to also account for the natural motion of the user's arm during exercise. It should also be understood, and as described elsewhere herein, that in some embodiments of the invention the apparatus **100** can come in any weight as long as the requisite dimensional and/or weight ratios are maintained.

FIG. 2A is a perspective view of a 35 lb center mass bell apparatus **200**, in accordance with an exemplary embodiment of the invention. It should be understood that each of the center mass bell apparatuses that are described herein bear similar structural features and for efficiency description will not be repeated for each alternative embodiment. Instead, notable differences in some embodiments of the invention are described.

For example, the center mass bell apparatus can come in different weights which, in some embodiments of the invention, may alter the dimensions of the apparatus as more material mass is added or subtracted in order to imbue it with more or less weightiness. Increased mass, relative to the center mass bell **100**, is optionally effectuated by increasing the size of the apparatus **200**, in an embodiment of the invention and/or is thicker and/or has a larger outer diameter. In some embodiments of the invention, the apparatus is made from a more or less dense material and/or the sides themselves are hollow (in addition to having a hollow **306** (shown in FIG. 3D).

In an embodiment of the invention, the center mass bell apparatus **200** has an approximate height of 7.006 inches and a radius from a center point of an imaginary sphere traced by the apparatus **200** of 4.25 inches (both shown in FIG. 2B), an external diameter of approximately 8.5 inches, and an opening **202** diameter of approximately 4.5 inches (both shown in FIG. 2B). In an embodiment of the invention, the hand hold **204** is approximately 1.0-2.5 inches in maximum diameter. In an embodiment of the invention, the hand hold **204** is approximately 1.2 inches in maximum diameter (shown in FIG. 2C).

It should be understood, that these dimensions are by way of example only, and that in different embodiments the dimensions are larger or smaller as long as three dimensional weight balance is maintained and that the ratio of the outer diameter squared to the height of the weight is under 21 and the ratio of the weight to the square of the outer diameter times the height is under 0.08. Optionally, the ratio of the outer diameter squared to the height of the weight is approximately 10.31. Optionally, the ratio of the weight to the square of the outer diameter times the height is approximately 0.069.

FIG. 3A is a side view of a 50 lb center mass bell apparatus **300**, in accordance with an exemplary embodiment.

ment of the invention. The dimensions for the apparatus **300** are slightly different than for apparatuses **100**, **200**. In an embodiment of the invention, the center mass bell apparatus **300** has an approximate height of 8.198 inches and a radius from a center point of an imaginary sphere traced by the apparatus **300** of 4.75 inches, an external diameter of approximately 9.5 inches, and an opening **302** diameter of approximately 4.5 inches (both shown in FIG. 3B). In an embodiment of the invention, a hand hold **304** is approximately 1.5 inches in maximum diameter (also shown in FIG. 3B).

It should be understood, that dimensions described in this application are by way of example only, and that in different embodiments the dimensions are larger or smaller as long as three dimensional weight balance is maintained and that the ratio of the outer diameter squared to the height of the weight is under 21 and the ratio of the weight to the square of the outer diameter times the height is under 0.08. Optionally, the ratio of the outer diameter squared to the height of the weight is approximately 11.01. Optionally, the ratio of the weight to the square of the outer diameter times the height is approximately 0.068.

FIG. 3C is a side view of the 50 lb center mass bell apparatus **300** showing the cross-section A-A of FIG. 3D, in accordance with an exemplary embodiment of the invention. FIG. 3D is the cross-sectional view of the 50 lb center mass bell apparatus **300**, in accordance with an exemplary embodiment of the invention. It should be understood that the cross-sectional views of each of the apparatuses **100**, **200**, **300**, **400** described herein are substantially similar in configuration, with dimensions varying slightly.

In an embodiment of the invention, the hand hold **304** is located in a hollow portion **306** of the apparatus **300** such that the weight of the apparatus is balanced (evenly spread) in three dimensions from the center of the apparatus **300** when the hand hold **304** is gripped by a user, for example the hand hold **304** is located equidistant from the top **308** and bottom **310** and/or is located at the maximum diameter of the imaginary circle circumscribed by the cross-sectional profile of the apparatus **300**. Optionally, the hand hold **304** does not extend all the way across and/or unbroken across the hollow **306**. FIG. 4A is a perspective view of a 70 lb center mass bell apparatus **400**, in accordance with an exemplary embodiment of the invention. The dimensions for the apparatus **400** are slightly different than for apparatuses **100**, **200**, **300**. In an embodiment of the invention, the center mass bell apparatus **400** has an approximate height of 9.365 inches and a radius from a center point of an imaginary sphere traced by the apparatus **400** of 5.25 inches (both shown in FIG. 4B), an external diameter of approximately 10.5 inches, and an opening **402** diameter of approximately 4.5 inches (both shown in FIG. 4C). In an embodiment of the invention, a hand hold **404** is approximately 1.0-2.5 inches in maximum diameter (also shown in FIG. 4C).

It should be understood, that dimensions described in this application are by way of example only, and that in different embodiments the dimensions are larger or smaller as long as three dimensional weight balance is maintained and that the ratio of the outer diameter squared to the height of the weight is under 21 and the ratio of the weight to the square of the outer diameter times the height is under 0.08. Optionally, the ratio of the outer diameter squared to the height of the weight is approximately 11.77. Optionally, the ratio of the weight to the square of the outer diameter times the height is approximately 0.068.

FIG. 5 is a flowchart **500** showing a method of using a center mass bell apparatus **100**, **200**, **300**, **400**, in accordance

with an exemplary embodiment of the invention. In an embodiment of the invention, a lifter/user of the center mass bell apparatus 300 grabs (504) the hand hold 304 in the center of the apparatus by inserting (502) a hand through an opening to the hollow 306. In an embodiment of the invention, because the center mass bell apparatus 300 is symmetrical, the user's hand can be inserted either from the top 308 or the bottom 310 of the apparatus in order to grab the hand hold. The user commences exercise (506) by maneuvering the center mass bell apparatus 300 from the centrally located hand hold as the contact point between the lifter and the apparatus. In an embodiment of the invention, maneuvering comprises lifting and/or lowering the apparatus. Optionally, exercising through maneuvering is repeated. In some embodiments of the invention, because the edges of the apparatuses are beveled at the openings, and they therefore stack evenly onto each other, a plurality of apparatuses can be used simultaneously for exercise. For example, the user having one in each hand and putting them together beveled opening to beveled opening.

The terms "comprises", "comprising", "includes", "including", "having" and their conjugates mean "including but not limited to".

The term "consisting of" means "including and limited to".

The term "consisting essentially of" means that the composition, method or structure may include additional ingredients, steps and/or parts, but only if the additional ingredients, steps and/or parts do not materially alter the basic and novel characteristics of the claimed composition, method or structure.

As used herein, the singular form "a", "an" and "the" include plural references unless the context clearly dictates otherwise. For example, the term "a compound" or "at least one compound" may include a plurality of compounds, including mixtures thereof. Throughout this application, various embodiments of this invention may be presented in a range format. It should be understood that the description in range format is merely for convenience and brevity and should not be construed as an inflexible limitation on the scope of the invention. Accordingly, the description of a range should be considered to have specifically disclosed all the possible subranges as well as individual numerical values within that range. For example, description of a range such as from 1 to 6 should be considered to have specifically disclosed subranges such as from 1 to 3, from 1 to 4, from 1 to 5, from 2 to 4, from 2 to 6, from 3 to 6 etc., as well as individual numbers within that range, for example, 1, 2, 3, 4, 5, and 6. This applies regardless of the breadth of the range.

Whenever a numerical range is indicated herein, it is meant to include any cited numeral (fractional or integral) within the indicated range. The phrases "ranging/ranges between" a first indicate number and a second indicate number and "ranging/ranges from" a first indicate number "to" a second indicate number are used herein interchangeably and are meant to include the first and second indicated numbers and all the fractional and integral numerals therebetween.

It is appreciated that certain features of the invention, which are, for clarity, described in the context of separate embodiments, may also be provided in combination in a single embodiment. Conversely, various features of the invention, which are, for brevity, described in the context of a single embodiment, may also be provided separately or in any suitable subcombination or as suitable in any other described embodiment of the invention. Certain features

described in the context of various embodiments are not to be considered essential features of those embodiments, unless the embodiment is inoperative without those elements.

5 Although the invention has been described in conjunction with specific embodiments thereof, it is evident that many alternatives, modifications and variations will be apparent to those skilled in the art. Accordingly, it is intended to embrace all such alternatives, modifications and variations 10 that fall within the spirit and broad scope of the appended claims.

All publications, patents and patent applications mentioned in this specification are herein incorporated in their entirety by reference into the specification, to the same extent as if each individual publication, patent or patent application was specifically and individually indicated to be incorporated herein by reference. In addition, citation or identification of any reference in this application shall not be construed as an admission that such reference is available as 15 prior art to the present invention. To the extent that section headings are used, they should not be construed as necessarily limiting.

20 What is claimed is:

1. A center mass bell apparatus, comprising:

25 a main body shaped substantially like a hollow sphere with spherical caps removed in a same central axis of the body to create two opposing and where the main body is balanced in at least three dimensions from a center point of the sphere and having a height of 5.786 inches, an external diameter of 7.5 inches and a weight of 20 lb; and,

a hand hold traversing centrally through the hollow of the spherical main body transverse to the central axis.

2. The apparatus according to claim 1 where the ratio of 30 the outer diameter squared to the height of the weight is under 21.

3. The apparatus according to claim 1 where the ratio of the weight to the square of the outer diameter times the height is under 0.08.

4. The apparatus according to claim 1, where the openings have at least one beveled edge.

5. The apparatus according to claim 1, where the main body and hand hold are of unitary construction.

6. A center mass bell apparatus, comprising:

45 a main body shaped substantially like a hollow sphere with spherical caps removed in a same central axis of the body to create two opposing and where the main body is balanced in at least three dimensions from a center point of the sphere and having a height of 7.006 inches, an external diameter of 8.5 inches and a weight of 35 lb; and,

a hand hold traversing centrally through the hollow of the spherical main body transverse to the central axis.

7. The apparatus according to claim 6, where the ratio of 55 the outer diameter squared to the height of the weight is under 21.

8. The apparatus according to claim 6, where the ratio of the weight to the square of the outer diameter times the height is under 0.08.

9. The apparatus according to claim 6, where the openings have at least one beveled edge.

10. The apparatus according to claim 6, where the main body and hand hold are of unitary construction.

11. A center mass bell apparatus, comprising:

50 a main body shaped substantially like a hollow sphere with spherical caps removed in a same central axis of the body to create two opposing openings and where

the main body is balanced in at least three dimensions from a center point of the sphere and having a height of 8.198 inches, an external diameter of 9.5 inches and a weight of 50 lb; and,

a hand hold traversing centrally through the hollow of the 5 spherical main body transverse to the central axis.

12. The apparatus according to claim 11, where the ratio of the outer diameter squared to the height of the weight is under 21.

13. The apparatus according to claim 11, where the ratio of the weight to the square of the outer diameter times the height is under 0.08.

14. The apparatus according to claim 11, where the openings have at least one beveled edge.

15. The apparatus according to claim 11, where the main 15 body and hand hold are of unitary construction.

16. A center mass bell apparatus, comprising:
a main body shaped substantially like a hollow sphere
with spherical caps removed in a same central axis of

the body to create two opposing openings and where the main body is balanced in at least three dimensions from a center point of the sphere and having a height of 9.365 inches, an external diameter of 10.5 inches and a weight of 70 lb; and,

a hand hold traversing centrally through the hollow of the spherical main body transverse to the central axis.

17. The apparatus according to claim 16, where the ratio of the outer diameter squared to the height of the weight is under 21.

18. The apparatus according to claim 16, where the ratio of the weight to the square of the outer diameter times the height is under 0.08.

19. The apparatus according to claim 16, where the openings have at least one beveled edge.

20. The apparatus according to claim 16, where the main body and hand hold are of unitary construction.
